US0D1040599S

(12) **United States Design Patent** (10) **Patent No.:** **US D1,040,599 S**
(45) **Date of Patent:** **** Sep. 3, 2024**

(54) **CAKE-POP MOLD**

(71) Applicant: **Fancy Sprinkles LLC**, Pacoima, CA
(US)

(72) Inventor: **Qi Guo**, Yiwu (CN)

(73) Assignee: **Fancy Sprinkles LLC**, Pacoima, CA
(US)

(**) Term: **15 Years**

(21) Appl. No.: **29/889,769**

(22) Filed: **Apr. 17, 2023**

Related U.S. Application Data

(63) Continuation of application No. 29/783,974, filed on May 17, 2021.

(51) **LOC (14) Cl.** **07-02**

(57) **CLAIM**

The ornamental design for a cake-pop mold, as shown and described.

DESCRIPTION

FIG. 1 is a perspective view showing my new design; FIG. 2 is a top view thereof;

FIG. 3 is a bottom view thereof;

FIG. 4 is a front side view thereof;

FIG. 5 is a back side view thereof;

FIG. 6 is a right side view thereof; and,

FIG. 7 is a left side view thereof.

The broken lines shown in the drawings are for the purpose of illustrating portions of the cake-pop mold that form no part of the claimed design.

1 Claim, 7 Drawing Sheets
